UNITED STATES PATENT OFFICE.

WILLARD F. RICHARDS, OF LANCASTER, NEW YORK, ASSIGNOR TO GOULD COUPLER CO., OF NEW YORK, N. Y.

JOURNAL-BOX.

1,335,298.

Specification of Letters Patent. Patented Mar. 30, 1920.

Application filed July 8, 1918. Serial No. 243,873.

To all whom it may concern:

Be it known that I, WILLARD F. RICHARDS, a citizen of the United States, residing at Lancaster, in the county of Erie and State 5 of New York, have invented a new and useful Improvement in Journal - Boxes, of which the following is a specification.

This invention relates to car journal boxes and more particularly to the spring devices 10 used for closing the lids thereof and releasably holding the lids in their closed and open positions.

In the M. C. B. journal boxes commonly in use the lid is hinged at its upper end to 15 a hinge lug on top of the journal box and a leaf spring or flat spring plate fixed at its lower end on the inside of the lid bears at its free upper end against the hinge lug. The spring bears on a flattened outwardly 20 facing surface of the hinge lug for holding the lid closed, and when the lid is raised the spring passes over the upper corner of the lug and bears on the top of the lug, thereby holding the lid open. The spring 25 is flexed or strained in thus passing over the corner of the lug from one to the other of its two holding positions. These springs must be relatively stiff in order to hold the 30 lids tightly closed, and since the free or movable portions of the springs are necessarily relatively short on account of the 35 small size of the lids, they are frequently broken or become permanently set and are therefore a source of much expense and trouble.

The object of this invention is to provide an efficient and reliable spring device for closing the lids of car journal boxes and releasably holding them in the closed and open 40 positions, which is of simple and inexpensive construction, is more flexible than the leaf springs heretofore used and is less liable to be broken or to become permanently set, and which enables lids equipped with 45 the device to be used on M. C. B. journal boxes now in use to replace the lids thereof which have been broken or lost.

In the accompanying drawings:

Figure 1 is an elevation, partly in section, of the outer end of a journal box provided with a lid closing or holding device embodying the invention.

Fig. 2 is a sectional elevation thereof on line 2—2, Fig. 1, showing by full and broken

lines the closed and open positions of the 55 lid.

A represents the journal box, the outer end portion only of which is shown, and B the lid for closing the usual opening or mouth *a* in the outer end of the journal box. 60 The lid is suitably hinged at its upper end to the box to swing upwardly and downwardly, for instance by a hinge pin *c* passing through bearings or hinge lugs *c'* on the lid and through a hinge lug *C* on the 65 box projecting upwardly between the lugs *c'* on the lid. The outer portion of the journal box including this hinge lug *C* is preferably of the construction commonly employed in M. C. B. journal boxes, so that 70 lids with the closing and holding devices forming the subject of this invention can be used on M. C. B. journal boxes now in use to replace the usual M. C. B. lids. The lug *C* has the usual flattened front or outer face 75 *c²* between the ends of the lug against which the upper end of the spring closing device on the lid bears to hold the lid closed, and a flattened top or upper face *c³* against which the closing device bears to hold the 80 lid open. *d* is the usual inwardly projecting marginal flange on the lid adapted to surround the mouth of the journal box for preventing the entrance of snow, rain and dust into the box.

The lid closing and holding spring device *E* consists of a spring rod or wire bent upon itself preferably into substantially M shape, thus forming two outer legs or upwardly extending members *e* and an intermediate downwardly extending loop or portion *e'* substantially parallel with and connected to the upper ends of the legs. The lower ends of the legs *e* are seated in sockets or perforated lugs *f* on the inside of 95 the lid at its lower portion and the bent lower end of the intermediate loop or downwardly extending portion *e'* of the spring enters a notch or seat *g* on the inside of the lid. The lower end of the loop *e'* presses 100 outwardly against the lid so that it is retained in the notch or seat *g* and thus secures the ends of the legs *e* in the sockets *f* against accidental displacement. When the lid is closed the upper end of the bent spring 105 *E* bears against the outer face *c²* of the hinge lug above the axis of the hinge and presses and holds the lid tightly against the

outer end of the journal box, forming a tight closure for the mouth *a*. When the lid is raised the upper end of the spring is flexed and passes over the corner of the lug *C* and bears on the flattened upper face *c*³ of the lug as indicated by the broken lines in Fig. 2, thereby holding the lid open.

The bent spring rod having a plurality of parts or members secured at their lower portions to the lid and bearing at their connected upper portions against the hinge lug *C*, as explained, has greater flexibility or elasticity than a straight or single-part spring of equal cross section. While, therefore, the spring described has adequate strength to press the lid firmly against the box and hold it in the intended positions, it is more durable and less liable to become permanently set than a single-part spring.

I claim as my invention:—

1. The combination with a journal box having a hinged lid, of a lid closing spring of substantially M-shape having a plurality of connected substantially straight parts secured at one end thereof to said lid and having the opposite connected end portion thereof arranged to bear against surfaces on the box adjacent the lid hinge for closing the lid and holding it open.
2. The combination of a journal box having a hinged lid, of a lid closing spring consisting of an upwardly extending substantially straight spring rod having one end thereof seated in a socket on the lid and a downwardly extending part connected to

the other end thereof, the lower end of which downwardly extending part enters a seat on the lid and thereby retains said first mentioned end in said socket, the connecting bent portion of the spring rod being arranged to bear against surfaces on the box adjacent the lid hinge for closing the lid and holding it open.

3. The combination with a journal box having a hinged lid, of a lid closing spring consisting of a bent spring rod having opposite legs secured at their ends to the lid and a loop between the legs, the portion of the spring connecting said loop and legs being arranged to bear against surfaces on the box adjacent the lid hinge for closing the lid and holding it open.

4. The combination with a journal box having a hinged lid, of a lid closing spring consisting of a bent spring rod having opposite legs seated at their ends in sockets on the lid and a loop between the legs, the portion of the spring connecting said loops and legs being arranged to bear against surfaces on the box adjacent the lid hinge for closing the lid and holding it open, and said loop engaging a part of the lid and thereby retaining the ends of said legs in said sockets.

Witness my hand this 5th day of July, 1918.

WILLARD F. RICHARDS.
